UNITED STATES PATENT OFFICE

WARREN H. PARKER, OF OAKLAND, CALIFORNIA, ASSIGNOR OF ONE-HALF TO
ANTHONY JORSKI, OF OAKLAND, CALIFORNIA

INTERNAL COMBUSTION ENGINE

Application filed July 2, 1928. Serial No. 289,870.

The invention relates to internal combustion engines.

An object of the invention is to provide an internal combustion engine in which a power impulse will be transmitted to the engine shaft not only by the piston but as well by the cylinder head between which and the piston the fuel charge is ignited.

Another object of the invention is to provide an engine of the character described, in which the usual vibration prevailing in the operation of engines of the internal combustion type will be practically eliminated.

A further object of the invention is to provide an engine of the character described in which for a given movement of the piston, the compression and expansion of gases in the cylinder will take place at a much greater rate than in engines heretofore in use.

20 A still further object of the invention is to provide an engine with the foregoing features which will be extremely simple in construction, and may be readily assembled and disassembled.

25 The invention possesses other objects and features of advantage, some of which, with the foregoing, will be set forth in the following description of the preferred form of the invention which is illustrated on the drawings accompanying and forming part 30 of the specification. It is to be understood, however, that variations in the showing made by the said drawings and description may be adopted within the scope of the invention as 35 set forth in the claims.

Referring to said drawings:

Figure 1 is a longitudinal sectional view taken through a multi-cylinder engine embodying the invention.

40 Figure 2 is a similar sectional view taken at right angles to Figure 1, the plane of the section being indicated by the line 2-2 of said latter figure.

45 Figure 3 is a cross sectional view taken through one of the cylinders, the plane of the section being indicated by the line 3-3 of Figure 1.

50 Figures 4 to 11 inclusive are diagrammatic representations showing the position

of the engine parts at different points in the operation of the engine.

The engine in the embodiment illustrated in the drawings comprises a casing 12, the lower portion thereof providing a crank case 55 13 while the upper portion provides a guide block 14. Arranged within the block 14 is a cylinder 16 having its upper end closed by a head 17 here shown as an integral part of the cylinder. A piston 18 is mounted for reciprocation within the cylinder and is operatively connected in the usual manner to a crank shaft 19 by means of a connecting rod 21.

Like the piston 18, the cylinder 16 together with its head 17 is mounted for longitudinal 65 reciprocal movement, and is preferably directly connected to the crank shaft by means of a pair of connecting rods 22 positioned on opposite sides of the piston connecting rod 21. As previously noted, the crank shaft is arranged to receive a power impulse from the cylinder as well as from the piston, and since the cylinder and piston are arranged to move in opposed directions during the power stroke, the rods 21 and 22 are connected to 70 the crank shaft 180 degrees apart.

75 Suitable means are provided for permitting the introduction of a charge of combustible mixture to the cylinder and the discharge therefrom of the mixture after it is ignited and spent. As here shown, the cylinder is provided with inlet and outlet ports 23 and 24 preferably positioned at opposite sides thereof and arranged respectively to periodically register with a fuel intake passage 25 and exhaust passage 26 provided in the block. The engine in its present embodiment is adapted to operate as a four stroke cycle unit, and in order that communication between the cylinder ports and the block passages will not be established at intervals involving less than two forward and return strokes of the piston, valves 27 and 28 are interposed between the said ports and 80 passages. The valves as here shown are in the form of segments which together define what may be termed a cylindrical sleeve which embraces the cylinder and engages in the bore 29 of the block. The segments are arranged 85 for reciprocative movement and are separate- 100

ly actuated from a valve actuating shaft 31 through the medium of eccentric straps 32 and 33, the former being connected to the segment 27 and the latter being connected 5 to the segment 28. Formed respectively in the segments 27 and 28 are ports 34 and 35 which during the reciprocation of segments move into and out of registry with the cylinder ports and the block passages.

- 10 The valve shaft 31 is driven by the engine shaft such as through gears 30 whereby the former will rotate once for every two revolutions of the latter, and as will be apparent by reference to Figures 4 to 11 inclusive of
15 the drawings, during the operation of the engine, once in every two revolutions of the engine shaft, to-wit at the commencement of the intake stroke of the piston, the port 34 will simultaneously communicate with the
20 inlet passage 25 and the port 23 thereby allowing the combustible mixture to enter the cylinder. Likewise once during every two revolutions of the engine shaft the port 35 will simultaneously register with the port 24 and
25 the exhaust passage 26, thus permitting the exhaust of the spent gases in the cylinder.

It is to be noted that due to the fact that the cylinder head moves toward the piston during the compression stroke, with a given stroke of piston and bore of cylinders, the compression of the charge introduced into the cylinder will be far greater than that obtained under the same conditions in an engine having a fixed cylinder head. It will also be noted that since the cylinder head is movable and transmits to the engine shaft the force of the impact of the ignited gases, not only is the torque of the shaft increased but the shock to the engine frame and the resultant vibration such as is produced by the impact against a fixed cylinder head, is practically entirely eliminated.

45 Ignition of the charge in the cylinder is here shown arranged to be effected by means of a spark plug 36 mounted in the cylinder head, electric connection between the plug and a source of current being maintained by means of a fixed insulated brush 37 frictionally engaging the electrode 38 of the plug.

50 Means are also provided for regulating the temperature of the engine in a novel and effective manner and practically without the addition of any auxiliary mechanism. Fixed to the block 14 and extending thereover is a hood 39 defining a closed chamber 41 with which the bore 29 is in direct communication. Due to the displacement of the cylinder in the bore during the operation of the engine, the pressure in the chamber 41 will vary, and advantage of this feature is taken to draw into such chamber fresh cold or hot air to correspondingly cool or warm the engine as may be desired. Both cold or hot air is arranged to be drawn separately into the chamber 65 through an intake pipe 42, one branch 43

thereof being open to the atmosphere, while another branch 44 communicates with the heater 45 in thermal contact with the exhaust pipe 46 of the engine. A check valve 47 and air cleaner 48 are disposed in the pipe 42, the former serving to permit air to be drawn into the chamber when the pressure therein is less than atmospheric, but preventing the back flow of air through the pipe. Discharge of air from the chamber is allowed through a check valve 49 which acts to prevent the intake of air therethru. By means of a two way valve 51 arranged at the juncture of the branches 43 and 44, the hot air pipe may be placed in communication with the chamber while the cold air is thereby shut off from said communication, or vice versa, the cold air pipe may be open whereby the hot air will be shut off. It will now be clear that upon the completion of each forward and return stroke of the cylinder, fresh air will be drawn into the chamber and used air discharged therefrom, and that since the air in the chamber is permitted to enter well into the bore when the cylinder is in its inward position, the walls of the engine may be effectively cooled or heated as conditions may make desirable.

While I have here shown and described the intake and exhaust openings for the chamber 41 as valve controlled, such control may be eliminated, although such elimination renders the temperature control less effective. 95

As will readily be apparent from an inspection of the drawings, the various parts comprising the engine are all of simple construction and render the assembly and repair of the engine a simple matter. It will thus be seen that not only is the engine efficient in operation, but may be constructed at low cost and kept in proper condition with minimum effort and expense. 100 105

I claim:

1. In an internal combustion engine, a block having a bore open at one end, a cylinder having a head and arranged to reciprocate in said bore, a conduit communicating with the open end of said bore and having two air intake openings and a discharge opening, a two way valve for closing either intake opening and a check valve for the discharge opening arranged to open on the up stroke of said cylinder. 110

2. In an internal combustion engine, a block having a bore open at one end, a cylinder having a head and arranged to reciprocate in said bore, and means operative upon the reciprocation of said cylinder in said bore whereby cold or heated air may be separately drawn into said bore to cool the engine parts. 120

3. In an internal combustion engine a block having a bore open at its upper end, a cylinder having a head and arranged to reciprocate in said bore, a conduit communicating with said open end of the bore and having a 125

cold air intake opening, a hot air intake and a discharge opening, a check valve arranged between said intake openings and said bore to prevent discharge of air through said in-
5 take openings on the up strokes of the cylinder, a two way valve for controlling the in-
take of air through said intake openings and another check valve normally closing said discharge arranged to open only on the up
10 stroke of said cylinder.

In testimony whereof, I have hereunto set my hand at Oakland, California, this 23rd day of June, 1928.

WARREN H. PARKER.
